UNITED STATES PATENT OFFICE.

GLENN E. McFADDEN, OF LAKEWOOD, OHIO, ASSIGNOR TO ALFRED VESTER SONS, INC., OF PROVIDENCE, RHODE ISLAND, A CORPORATION OF RHODE ISLAND.

DESIGN FOR A HUSK FOR LIGHTING FIXTURES.

Application filed February 6, 1924. Serial No. 8,556. Term of patent 14 years.

To all whom it may concern:

Be it known that I, GLENN E. McFADDEN, a citizen of the United States, and residing at Lakewood, in the county of Cuyahoga and State of Ohio, have invented a new, original, and ornamental Design for Husk for Lighting Fixtures, of which the following is a specification, reference being

had to the accompanying drawing, forming part thereof.

The figure shown in the drawing is a perspective view showing my new design.

I claim:

The ornamental design for a husk for lighting fixtures as shown.

GLENN E. McFADDEN.
